UNITED STATES PATENT OFFICE

ALBERT M. GRUBBS, OF WARSAW, INDIANA

PAN LIFTER

Application filed November 23, 1929. Serial No. 409,374.

This invention relates to improvements in implements intended for the handling conveniently of relatively light utensils such as pans, plates, flat type dishes and the like.

In the present embodiment the invention is of form, structure and proportions especially adapted for use in handling of pans in which pies are contained, and it is designated as a pan lifter.

Objects of the invention are to provide a device of the kind described which is economical of manufacture, light in weight, and easy to use, and which is not liable to get out of order or repair.

15 In the drawings—

Figure 1 is a side view of my improved pan lifter.

Figure 2 is a top plan view of Figure 1.

Figure 3 is an enlarged vertical cross section view on line 3—3 in Figure 1.

Figure 4 is an enlarged vertical cross section view on line 4—4 in Figure 1.

Figure 5 is an enlarged vertical cross section view on line 5—5 in Figure 1.

25 My invention has especial reference to improvements in a device of the class referred to which consists of a handle, a reach member thereon, and whose forward end is provided with a cross arm, the end portions of

30 which are disposed downwardly and are provided with inturned fingers, a holder member retained in slidable relation with the handle, its forward end being downwardly disposed and provided with a flange and being

35 slidingly co-engaged with the reach member, and means provided on the handle whereby the holder member may be fastened at the varied positions to which it may be moved. The features of my said improvements are clearly described and illustrated in the following specification, and annexed drawings, and the invention is defined in the appended claims.

The handle 1 may be of wood, about twelve 45 inches in length. The reach member consists of complementary wires 2 and 2, about one-eighth of an inch in diameter, the forward portions, 2^a, of which are bent at right angles, and are wrapped one upon the other, 50 and which constitute a cross arm 5. The said

cross arm 5 is provided with downwardly disposed end bends 6, and inwardly disposed fingers 7. The rear portions 2^b of the wires 2 are seated in grooves, 1^a, therefor, in the sides of the handle, and the ends of said wires are inturned and driven into the sides of the handle. By means of staples 8 the said wires are held securely united with the handle. 55

The holder member may be of flat bar metal seven-eighths of an inch wide, its body portion 10 having a downwardly disposed bend 11, and forwardly projected flange 12; a cross head 13 which is secured by rivets or by welding to the said bend 11, has spaced 60 grooves 14 which engage with the wires 2 and 2. The upturned end 15 of said bar constitutes a head against which the user's thumb or finger may be disposed, as will be presently referred to. 65

A threaded stud 16 which is fixed in the said handle, and whose end portion is engaged by the slot 17 of the holder member, is provided with a suitable wing-nut 18. 70

The structural features of the invention are shown in the preferred forms, however it will be understood that modifications may be made therein without departing from the spirit of the invention or sacrificing any of its advantages. 75

In an embodiment of the invention in form for handling pans or vessels of smaller than the 10 inch standard pie pan shown, the cross arm is made of decreased length.

Whereas my invention is described as being especially adapted for the handling of pans, it obviously is useful for the picking up, lifting, and transposing of articles of any kind having rim or marginal portions with which the fingers 7 of the cross arm 90 and the flange 12 of the holder member may be engaged.

An implement constructed in accordance with my invention is relatively light in weight, is extremely economical of manufacture, and it is capable of being easily and effectively used by a person of only ordinary skill. 95

The holder member when at the retracted position (as shown by the dotted lines) per- 100

mits of the disposing of the reach member in engagement with a pan A of maximum size. The depth of the end bends 6 are such that when the fingers 7 are in engagement with the rim of the pan, there is ample clearance of the reach member wires 2 above the pan. The implement having been thus disposed, with the fingers at its cross arm in engagement with the underside of the pan rim, the user then shifts the holder member forwardly, its flange 12 being in position underneath the portion A' of the rim of the pan. By exertion of only a slight pressure against the head of the holder, the latter is held against movement, and the pan is retained firmly for such disposition as may be desired. To release the pan, the user simply retracts the holder, the flange 12 thus being moved clear of the pan rim. The implement then is completely unattached, and may be removed readily, the pan having been reposed at desired location, and the contents of the pan being undisturbed.

In instances where for any reason it may be desired to retain the pan a period of time other than that necessary simply in the lifting of and transposing same to a nearby place, or if the place at which the pan is to be deposited is such that the retention of the holder member by the user's hand might be inconvenient, the wing nut 18 is screwed down, thereby tightening and securing the holder member at the position to which it may have been moved.

Within the scope of the invention as it is defined in the appended claims, modifications in the several parts and in the details thereof may be made without departing from the general principles of the invention.

What I claim as my invention and desire to secure by Letters Patent is—

1. An implement of the kind described, comprising a handle, aligned parallel reach wires having their rear portions secured to the handle, their forward portions being bent at right angles, one being wrapped upon the other and thence being extended in opposite directions to constitute a cross arm, the end portions of said cross arm being bent downwardly and provided with inturned fingers, and a holder member operable slidably on said reach wires, the cross head thereof having a forwardly disposed flange.

2. An implement of the kind described, comprising a handle, aligned parallel reach wires having their rear portions secured to the handle, their forward portions being united to each other and being bent at right angles to constitute a cross arm, the end portions of said cross arm being bent downwardly and provided with inturned fingers, and a holder member operable slidably on

said reach wires, the cross head thereof having a forwardly disposed flange.

3. An implement of the kind described, comprising a handle, aligned parallel reach wires having their rear portions secured to the handle, their forward portions being united to each other and being bent at right angles to constitute a cross arm, the end portions of said cross arm being provided with inturned fingers, a holder member operable slidably on said reach wires, the cross head thereof having a forwardly disposed flange, and the body portion of said holder member being longitudinally slotted and having bearing against the handle, a threaded stud on the handle to engage the slot of said holder member, and a wing nut on said stud.
